UNITED STATES PATENT OFFICE.

GEORGE L. MURDOCK, OF SAN FRANCISCO, CALIFORNIA.

HEAD-REST FOR BATH-TUBS.

1,163,945.

Specification of Letters Patent. Patented Dec. 14, 1915.

Application filed September 22, 1914. Serial No. 863,026.

To all whom it may concern:

Be it known that I, GEORGE L. MURDOCK, a citizen of the United States, residing in the city and county of San Francisco and 5 State of California, have invented a new and useful Improvement in Head-Rests for Bath-Tubs, of which the following is a specification.

My invention relates to head rests for bath 10 tubs wherein a single wire, bent to form at once a securing and supporting means, operates in conjunction with a fabric strip, for the support of the head; and the objects of my invention are first, to provide an improved means for supporting the head of a bather at the inclined end of a bath tub; second, to provide a device of the character described that is durable and simple of construction; third, to provide a head rest that 15 may be produced cheaply; fourth, to provide a head rest that is adapted to engage the curved end of a bath tub; fifth, to provide a device of the character described that will support the head in comfort; sixth, to provide a device of the character described 20 wherein the fabric may be easily removed, washed and replaced; and seventh, to provide a head rest for bath tubs that will not be injured by dampness. I accomplish 25 these several features by means of the device disclosed in the drawings forming a part of the present specification wherein like characters of reference are used to designate similar parts throughout the said specification and drawings, and in which—

Figure 1 is a broken perspective view of the curved inclined end of a bath tub disclosing the invention attached thereto. Fig. 2 is a broken transverse sectional view of 40 the tub disclosing a front elevation of the head rest.

In order to provide a cheap, durable and comfortable head rest for a bath tub that may be easily and readily attached and detached, and also impervious to water, I have provided the device described as follows: A single U-shaped wire member has hooks 2 formed on the ends of the stems 3 thereof, said hooks 2 being arranged to engage the 45 curved end or roll 4 of a bath tub 5 as disclosed in Fig. 1 of the drawings. The lower portions 6 of the stems 3 are bent at an angle to the upper portions of the stems 3 so as to form a support which is arranged 50 to rest on the inclined portion of the tub 5 as disclosed in Fig. 1.

The connection 7 between the lower portions 6 of the stems 3 imparts a degree of rigidity to the frame comprising the U-shaped member and also acts as a separator 60 between the stems 3 and the lower portions 6 thereof.

Between the bent portions 6 and the hooks 2 a pliable double fabric 8 is secured around and between the stems 3 and serves as a resilient support for the head of the bather. 65

The U-shaped construction, while possessing a degree of rigidity sufficient to retain the shape and support the weight of a head, also possesses a certain degree of resiliency 70 between the ends of the stems 3 so that when a weight is resting on the fabric 8 the rigidity of the structure is not sufficient to prevent a slight movement of the said stems 3 toward each other. The pliable nature of 75 the rest 8 will also contribute toward the resiliency thereof so that a bather reclining within the tub may have his head comfortably supported.

It is evident that the pliable fabric head 80 rest 8 may be easily removed and washed and as easily replaced also that the entire structure may be easily and readily removed from the tub and as easily and as readily replaced. 85

Inasmuch as the parts are few and simple of construction it is obvious that it may be produced cheaply.

Having thus described my invention, what I claim as new and desire to secure by Letters Patent is—

1. A head rest for bath tubs comprising a U-shaped member having the ends thereof arranged to engage the curved end of a bath tub and the lower portion thereof bent to 95 rest on the inclined portion of a tub; and a suitable fabric secured between the stems of the U-shaped member and arranged to support the head.

2. A head rest for bath tubs comprising 100 a single U-shaped member having hooks formed on the ends thereof arranged to engage the curved end of a bath tub, the lower portion of the said member being bent at an angle to the upper portion thereof so as 105 to form a support adapted to rest on the inclined end of a bath tub; and a suitable fabric secured between the stems of the member above the lower bend and arranged to support the head. 111

3. A head rest for bath tubs comprising a single U-shaped member composed of a sin-

gle wire having hooks formed on the ends thereof arranged to engage the curved end of a bath tub and having the lower portion of said member bent at an angle to the upper portion, said lower portion being arranged to rest on the inclined portion of a bath tub and thereby form a support for the upper portion; and a double fabric secured around and between the portions of the stems between the hooks on the ends

and the lower bent portion, said fabric being adapted to support the head.

In witness whereof, I have hereunto set my signature in the presence of two subscribing witnesses.

GEORGE L. MURDOCK.
